[57] CLAIM

The ornamental design for a clothes dryer rack, as shown and described.

DESCRIPTION

FIG. 1 is a front elevational view of the clothes dryer rack showing my new design;

FIG. 2 is a right side elevational view thereof;

FIG. 3 is a top plan view;

FIG. 4 is a bottom plan view;

FIG. 5 is a front elevational view of the clothes dryer rack when collapsed;

FIG. 6 is a right side elevational view of the collapsed clothes dryer rack;

FIG. 7 is a top plan view thereof; and

FIG. 8 is a bottom plan view thereof.

The rear elevational views of my clothes dryer rack in the assembled and collapsed forms are the same as FIGS. 1 and 5, respectively and the left side elevational views thereof are the same as FIGS. 2 and 6, respectively.

FIG. 1

FIG. 2

FIG. 3

FIG. 4

FIG. 5

FIG. 6

FIG. 7

FIG. 8
